US0D1076505S

(12) **United States Design Patent** (10) **Patent No.:** **US D1,076,505 S**
(45) **Date of Patent:** **** May 27, 2025**

(54) **STORAGE RACK**

(71) Applicant: **Shenzhen Nuozhe Technology Co., Ltd**, Shenzhen (CN)

(72) Inventor: **Yinan Zou**, Guangdong (CN)

(73) Assignee: **Shenzhen Nuozhe Technology Co., Ltd**, Shenzhen (CN)

(**) Term: **15 Years**

(21) Appl. No.: **29/991,955**

(22) Filed: **Mar. 5, 2025**

(51) **LOC (15) Cl.** **06-04**

(52) **U.S. Cl.**

USPC **D6/567**

(58) **Field of Classification Search**

USPC D6/553, 548, 552, 566, 567, 569, 581,

D6/572; D8/363, 373, 380

CPC A47F 5/08; A47F 5/0853; A47F 5/0807;

A47G 25/0678; A47G 29/08; B25H 3/04

(57) **CLAIM**

The ornamental design for a storage rack, as shown and described.

DESCRIPTION

FIG. 1 is a perspective view of a storage rack showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

FIG. 9 is a perspective view of the storage rack in a state of use.

The portions of the storage rack are shown in broken lines form no part of the claimed design. The other broken lines illustrate environmental subject matter that form no part of the claimed design.

1 Claim, 9 Drawing Sheets
